FILM CUT-OUT

Leon Joachim Barwood, Cambridge, Mass.

Application August 16, 1935, Serial No. 36,489

17 Claims. (Cl. 200—118)

The present invention relates to film cut-outs, and its object is to provide a new and improved film cut-out that shall be simple in construction, cheap to manufacture, very efficient in operation, and exceedingly uniform in its dielectric characteristics and consequent break-down voltage.

According to the invention disclosed in Letters Patent No. 2,014,409, granted September 17, 1935, the conducting members of the film cut-out are disposed in the opening of a ring-shaped, insulating member the friction of the peripheries of the conducting members against the wall of the opening being sufficient to hold the parts together as a unit, particularly if the diameter of the conducting members is somewhat larger than that of the opening. The wall of the opening may be torus-shaped to aid this holding action.

An object of the present invention is to provide an improved film cut-out of the above-described character provided with a greater curvature of the torus than is disclosed in the said Letters Patent.

The said Letters Patent discloses also a modification comprising two insulating members and a further object is to improve upon this modification also.

Other and further objects will be explained hereinafter and will be particularly pointed out in the appended claims.

The invention will be more fully described in connection with the accompanying drawings, in which Fig. 1 is an elevation of a film cut-out embodying the present invention; Figs. 2 and 4 are diametrical sections taken upon larger scales on the lines 2—2 of Fig. 1 and 4—4 of Fig. 3, respectively, looking in the directions of the arrows; Fig. 3 is a view similar to Fig. 1 of a modification; Figs. 5 and 6 are perspectives of parts of the embodiment shown in Figs. 3 and 4; Fig. 5 being partly broken away, for clearness; Fig. 7 is a view similar to Fig. 1 of a further modification; Fig. 8 is a section, but upon a larger scale, taken upon the line 8—8 of Fig. 7, looking in the directions of the arrows; and Fig. 9 is a perspective of a part of the modification shown in Figs. 7 and 8.

As described in the said Letters Patent, a film cut-out may comprise two preferably circular or disc-shaped, centrally bowed-out, members 2 and 4, of conducting material, like metal, such as aluminum, but insulated from each other in any desired manner. As illustrated in Figs. 1 to 4, a circular or disc-shaped, insulating, thin film 6 of tissue paper, silk or any other desired material,

may be disposed between and separating the conducting members, so as to contact with their non-bowed-out peripheral portions, thus providing an air chamber 18 between the insulating disc 6 and the centrally-bowed-out portion of each disc 2 and 4. As illustrated in Figs. 7 and 8, however, the separating film 6 may be omitted and the contacting, peripheral, inner surfaces of the metal members 2 and 4 may be covered with a suitable insulating coating 20 of an oxide of the metal. The oxide-coating modification may be embodied also in the modification illustrated by Figs. 3 and 4. As is also described in the said Letters Patent, the discs 2 and 4 and the film 6 may be held together mechanically, as a unit, merely by the peripheral edges of the discs 2 and 4 frictionally engaging the torus-shaped or concave wall 22 of the opening of a ring-shaped or annular, stiff-fibre, insulating disc 8.

According to a feature of the present invention, the curvature of the torus-shaped wall 22 is considerably enlarged, so as substantially to increase the height of its peripheral edges or projections 24. This may be effected in any suitable manner, as by means of a burring roll (not shown) that moves along the exterior surfaces of the ring 8, near, and along the circumference of, the opening, to produce a groove 26, thereby upsetting or plowing up or spreading the material of the insulating ring 8 into the opening of the ring.

The grooves 26 are not cuts in the material of the ring 8. The plowing up of the material of the ring is, rather, attended by a compression of the material in the grooves 26, thus hardening and strengthening the material in the neighborhood of the edges or projections 24. The edges or projections need not, of course, be continuous, they may be disposed at a plurality of separated positions along the circumference of the opening of the ring 8. The projections 24 thus engage the conducting discs 2 and 4 at their sides, near their peripheries only, more positively than in the said Letters Patent to hold the discs 2 and 4 more effectively in the opening of the ring 8.

As is further described in the said Letters Patent, the ring 8 may be replaced by two ring-shaped or annular, stiff-fibre, insulating discs 10 and 12, as shown in Figs. 3 to 8. The discs 10 and 12 may each be provided with an annular recess 14 surrounding its opening, the similar openings of the discs 10 and 12 being opposed to each other. The peripheries of the discs 2 and 4 may be held together mechanically, as a unit, in these recesses 14, the walls of the recesses 14

engaging the members 2 and 4 at their sides, near their peripheries only. The discs 10 and 12 are, in this case, each provided with projections 28 and 30, respectively, extending into corresponding

- 5 openings or recesses 38 of the conducting discs 2 and 4 and into the recesses 14. The annular discs 10 and 12 may be rigidly secured together, with the conducting discs 2 and 4 and the insulating film 6, in assembled position, by means of rivets 16 that extend through alined, 10 peripheral recesses 32 in corresponding, alined projections 28 and 30 and through recesses 38 in the insulating film 6. The rivets 16 need not necessarily be separate members, as illustrated, 15 but they may be formed integral with, or pressed out from, one of the discs 10 and 12.

It will be understood that the invention is not limited to the exact embodiments thereof that are herein illustrated and described, but that 20 further modifications may be made without departing from the spirit and scope of the invention as defined in the appended claims.

What is claimed is:

1. A film cut-out comprising two insulated conducting members, and means having an opening in which the conducting members are disposed, the material of the said means being displaced so as to extend into the opening at its exterior surfaces near the opening to provide the wall of the 25 opening with projections between which the conducting members and the means are held together as a unit.
2. A film cut-out comprising two insulated conducting members, and means having an opening 30 in which the conducting members are disposed, the material of the said means being displaced so as to extend into the opening at a plurality of positions along its exterior surfaces near the opening to provide the wall of the opening with 35 projections between which the conducting members and the means are held together as a unit.
3. A film cut-out comprising two insulated conducting members, and an insulating ring in the opening of which the conducting members are 40 disposed, the material of the ring being displaced so as to extend into the opening at a plurality of positions along its exterior surfaces near the opening to provide the wall of the opening with projections between which the conducting members and the ring are held together as a unit.
4. A film cut-out comprising two conducting members, an insulating film disposed between and separating the conducting members, and a member having an opening in which the conducting and the insulating members are disposed, the material of the member being displaced so 45 as to extend into the opening at its exterior surfaces near the opening to provide the wall of the opening with projections between which the conducting and the insulating members are held together as a unit in the opening.
5. A film cut-out comprising two insulated conducting members, two similar members each having an opening, one of the members having a peripheral recess, and means for mechanically holding the similar members together with the openings opposed to each other and with the conducting members disposed as a unit between the similar members and the opening, the mechanical holding means comprising means on the other member disposed in the peripheral recess of the 50 said one member.
6. A film cut-out comprising two insulated conducting members, two similar members each having an opening and a projection extending into 55

the opening, the projections being alined, the projections on one of the similar members having a recess, and means cooperating with the other member and disposed in the recess for mechanically holding the similar members together with the openings opposed to each other and with the conducting members disposed as a unit between the similar members and the opening.

7. A film cut-out comprising two insulated conducting members, two similar members each having an opening and a projection extending into the opening, the projections being alined and having alined recesses, and means extending through the recesses for mechanically holding the similar members together with the openings 15 opposed to each other and with the conducting members disposed as a unit between the similar members and the opening.

8. A film cut-out comprising two insulated conducting members, two similar members each having an opening and a plurality of projections extending into the opening, corresponding projections of the similar members being alined and having alined recesses, and means extending through corresponding recesses for mechanically 25 holding the similar members together with the openings opposed to each other and with the conducting members disposed as a unit between the similar members and the opening.

9. A film cut-out comprising two conducting 30 members, an insulating film disposed between and separating the conducting members, two similar insulating members each having a similar opening and a projection extending into the opening, the projections being alined, and means 35 cooperating with the projections for mechanically holding the similar members together with the openings opposed to each other and with the conducting members and the insulating film disposed as a unit between the similar members in 40 the openings.

10. A film cut-out comprising two insulated conducting members, and insulating means engaging the conducting members at their sides, 45 near their peripheries only for holding the conducting members and the insulating means together as a unit.

11. A film cut-out comprising two conducting members, an insulating film disposed between and separating the conducting members, and means 50 engaging the conducting members at their sides, near the peripheries only for holding the conducting members and the insulating film together as a unit.

12. A film cut-out comprising two insulated 55 conducting members, two similar members each having an opening and an annular recess surrounding the opening and a projection extending into the opening and the recesses, the projections being alined, the projections on one of the similar 60 members having a recess, and means cooperating with the other member and disposed in the recess for mechanically holding the similar members together with the openings opposed to each other and with the conducting members disposed as a 65 unit between the similar members and the opening, the conducting members having recesses for receiving the projections.

13. A method of making an insulating ring for a film cut-out comprising plowing up the material of the insulating ring into the opening of the ring.

14. A method of making a film cut-out comprising plowing up the material of an insulating ring into the opening of the ring at a plurality 75

of positions along its exterior surfaces near the opening to provide the wall of the opening with projections, and inserting insulated conducting members in the ring to cause them to be held together as a unit in the ring by the projections.

15. A film cut-out comprising two insulated conducting members, and insulating means engaging the conducting members at their edges, and also at their sides near their peripheries only, for holding the conducting members and the insulating means together as a unit.

16. A film cut-out comprising two conducting members, an insulating film disposed between and separating the conducting members, and

means engaging the conducting members at their edges and also at their sides near the peripheries only, for holding the conducting members and the insulating film together as a unit.

17. An insulating ring for a film cut-out, the material of the ring being displaced so as to extend into the opening at a plurality of positions along its exterior surfaces near the opening to provide the wall of the opening with projections between which insulated conducting members may be held together as a unit in the ring.

LEON J. BARWOOD.
